Primary Examiner — Ricky Pham(74) *Attorney, Agent, or Firm* — Diederiks & Whitelaw, PLC; John L. Crimmins(57) **CLAIM**

The ornamental design for a baking pan shield, as shown and described.

DESCRIPTION

FIG. 1 is a top perspective view of a baking pan shield, according to the present invention;

FIG. 2 is a top view of the baking pan shield of FIG. 1;

FIG. 3 is a bottom view of the baking pan shield of FIG. 1;

FIG. 4 is a right side view of the baking pan shield of FIG. 1;

FIG. 5 is a left side view of the baking pan shield of FIG. 1;

FIG. 6 is a front end view of the baking pan shield of FIG. 1; and,

FIG. 7 is a rear end view of the baking pan shield of FIG. 1. Where included, broken lines showing structural and/or other features in the invention of the baking pan shield are for illustrative purposes only and, as such, form no part of the claimed design.
